FIG. 1 is a top front perspective view of a remote controller for coordinate input device showing my new design;
FIG. 2 is a front view of the remote controller for coordinate input device of FIG. 1;

FIG. 3 is a left side view of the remote controller for coordinate input device of FIG. 1;

FIG. 4 is a right side view of the remote controller for coordinate input device of FIG. 1;

FIG. 5 is a top view of the remote controller for coordinate input device of FIG. 1;

FIG. 6 is a bottom view of the remote controller for coordinate input device of FIG. 1;

FIG. 7 is a cross-sectional view of the remote controller for coordinate input device of FIG. 1 along line 7-7 in FIG. 2; and,

FIG. 8 is a rear view of the remote controller for coordinate input device of FIG. 1.

The broken lines show portions of the remote controller for coordinate input device which form no part of the claimed design.
